UNITED STATES PATENT OFFICE

2,383,418

ESCAPEMENT

Marcus H. Rhodes, Hartford, Conn., assignor to
M. H. Rhodes, Inc., Hartford, Conn., a corpora-
tion of Delaware

Original application December 12, 1940, Serial
No. 369,693, now Patent No. 2,363,993, dated
November 28, 1944. Divided and this applica-
tion April 19, 1941, Serial No. 389,312

2 Claims. (Cl. 58—117)

This invention relates to escapements, and with
regard to certain more specific features, to im-
pulse escapements.

The invention is an improvement upon the
construction disclosed in Franz United States
Patent 1,934,611, dated November 7, 1933.

This application is a division of my United
States application Serial No. 369,693, filed Decem-
ber 12, 1940, for Escapement, eventuated as Pat-
ent No. 2,363,993, dated November 28, 1944.

Among the several objects of the invention may
be noted the provision of an escapement for con-
trolling gear trains and the like in which the
advantage is obtained of a radius of application
of the impulse, which is greater during at least
part of the time of the impulse, than the braking
radius of the escapement; the provision of an
escapement of the class described which is inde-
pendent in operation of the character of the
finish on the escapement teeth and in which a
quiet and smoothly acting recessive wiping con-
tact is attained; the provision of an escapement
of the class described in which hooking action is
avoided between a pallet and escapement teeth,
the latter, for purposes which will appear, being
formed unsymmetrically and sloping in the direc-
tion of their advance; and the provision of escape-
ment apparatus which is characterized by quiet-
ness and a large angle of action of the balance
staff. Other objects will be in part obvious and
in part pointed out hereinafter.

The invention accordingly comprises the ele-
ments and combinations of elements, features of
construction, and arrangements of parts which
will be exemplified in the structures hereinafter
described, and the scope of the application of
which will be indicated in the following claims.

In the accompanying drawing, in which are
illustrated several of various possible embodi-
ments of the invention,

Fig. 1 is a vertical section taken on line 1—1 of
Fig. 2, showing an escapement wheel, a balance
staff, and in part a hair spring;

Fig. 2 is a vertical section taken on line 2—2
of Fig. 1;

Fig. 3 is an enlarged fragmentary view of the
escapement wheel and balance staff in a position
succeeding that of Fig. 1;

Fig. 4 is a view similar to Fig. 3 showing a suc-
ceeding position; and,

Fig. 5 is a view similar to Fig. 4 showing an-
other succeeding position.

Similar reference characters indicate corre-
sponding parts throughout the several views of
the drawing.

In the construction of the Franz patent there is
a driving radius on the balance staff which is
greater at all times than the braking radius. It
is useful so long as the machine work is good on
the teeth of the escapement wheel, and as long
as the driving pin is used in conjunction with an
escapement tooth of a suitable angle to cam the
pin, instead of hooking in behind the pin as would
be the case if a ratchet type of driving tooth were
used. Also, if burrs occur at or near the ends of
the teeth, it sometimes happens that these act
as hooks behind the driven pin, thus holding the
pin and interfering with proper operation.

The present invention avoids this interference
without the necessity for removing burrs during
the manufacture of the escapement wheel and
also obtains improved results. This is done by
providing a pallet connection between what may
be considered the pin portion (in the patent) with
the grooved portion on the balance staff, so that
the escapement teeth function on this pallet, but
without the disadvantages of ordinary pallets.

Referring now more particularly to Figs. 1
and 2 herein, numerals 1 and 3 indicate spaced
frame plates for supporting the usual gear train
which the present escapement controls. The last
gear or pinion of the train is shown at 5 and it
is this gear that drives the escapement.

The gear 5 is attached to a shaft 7 to which
also is fastened a toothed escapement wheel 9
which, through the action of the gear train on
the gear 5, is biased to rotate in the direction
shown by the arrows. Solid arrows indicate
rotary conditions and dotted arrows indicate a
mere rotary bias without movement.

Numerals 11 indicates the balance staff carrying
a balance member 13. A vibratory hair spring 15
is also attached at one end to the balance staff 11
and anchored at the other end to the frame, as
indicated at wedge 17.

The center line of the balance staff 11 is only
slightly beyond the ends of the teeth 19 of the
escapement wheel 9, so that, in the absence of
any notch in the staff, the ends of the teeth 19 are
biased against the shaft. The teeth 19 are sub-
stantially in the same plane.

To provide for successive passage of the teeth
19, the shaft balance staff 11 is notched at 21.
To provide for driving the staff 11 from the es-
capement wheel 9, a radial plate 23 is attached to
the staff 11 and extends outward through the
plane of the notch. For convenience, this plate
may be referred to as a pallet. It extends beyond
the surface of the staff 11, and thus beyond the
notch 21.

The spaces 25 between the teeth 19 are deep enough to accommodate oscillations of the elongated pallet 23, as indicated. The forward faces of the teeth slope from their bottoms to their tops in the direction of their normal advance.

Operation is as follows:

The position of parts has been chosen in Fig. 1 to show tooth 19B resting against the staff 11. The parts are related in Fig. 3 to show the toothed escapement wheel 9 just released and about to move freely to the right under bias from the spring which drives the gear train meshed with the pinion gear 5. At this time the staff 11 with the pallet 23 is moving clockwise, under action of spring 15. The pallet passes to the left through the respective space 25 between teeth 19. The tooth 19A having just escaped, the tooth 19B is proceeding to pallet-pushing position.

In Fig. 4 the pallet 23 is shown as having proceeded clockwise to be met by the oncoming tooth 19B, which stops the clockwise rotation of the staff 11 and again forces it counterclockwise to the position shown in Fig. 5, the tooth 19B meanwhile escaping from under the pallet. The oncoming tooth 19C then strikes the braking surface 2 constituted by the cylindrical back of the staff 11. The staff 11 then continues to move counterclockwise while winding up the hair spring 15 and under the friction braking action of tooth 19C until the final stationary position of the staff 11 of Fig. 1 is reached, wherein the hair spring 15 is wound up. Thereafter the hair spring vibrates back and forces the staff 11 clockwise to release the tooth 19C into the notch 21, to be met subsequently by the pallet 23 to repeat the cycle.

It will be noted that, since the pallet 23 extends beyond the surface of the staff 11, the accelerating push on the staff is delivered at a radius which for at least a part of the time is greater than the braking radius at contact between a tooth and the braking surface 2 of the staff 11.

It will also be noted in the drawing that the teeth 19 are unsymmetrical and in effect slope in the direction of their advance, that is, they are ratcheted shaped. Stated otherwise they are forwardly hook shaped with a forward undercut. This is the general shape that, even if flat on the front face, would develop a hooking action behind the pin in the case of said Franz patent, and which is avoided by the radial pallet construction herein. The ratchet-shaped teeth are desired in many cases, though not all cases, because they deliver an initial power impulse which is superior to a non-ratchet type of tooth. This is because the impulse is to be delivered straight ahead at a line more or less perpendicular to the center line between the shafts 7 and 11.

The staff 11 has the notch 21 cut into it per se, without introducing an extra fitting. This produces a braking surface of practical minimum radius, which in some cases is desirable. At the same time, the radial pallet extends so that there is a substantial intersection with the path of the coplanar teeth 19.

In view of the above, it will be seen that the several objects of the invention are achieved and other advantageous results attained.

As many changes could be made in the above constructions without departing from the scope of the invention, it is intended that all matter contained in the above description or shown in the accompanying drawing shall be interpreted as illustrative and not in a limiting sense.

I claim:

1. An escapement mechanism comprising an escapement wheel having escapement teeth, all parts of which are substantially in a plane, said teeth having at least their forward faces sloping from their bottoms to their tops in the direction of their normal advance, an oscillating balance staff having a braking surface associated with said staff and a notch permitting escapement of said teeth successively and terminating the braking surface, and a pallet having a continuous pallet face extending from said notch to a point outside of the radius of the braking surface, said pallet face being adapted to be engaged by said teeth as they pass successively through said notch, said pallet face having a surface engaged by the teeth without a hooking action.

2. An escapement mechanism comprising an escapement wheel having escapement teeth, all parts of which are substantially in a plane, each tooth being shaped with a forward undercut portion, an oscillating balance staff having a braking surface associated with said staff and a notch permitting escapement of said teeth successively in the direction of their undercuts and terminating the braking surface, and a pallet having a continuous pallet face extending from said notch to a point outside of the radius of the braking surface, said pallet face being adapted to be engaged by the undercut portions of said teeth as they pass successively through said notch, the extension of the pallet and the undercut portions of the escapement teeth being such that during escape action of a tooth, the end portion of the pallet is first engaged at a relatively large radius on the pallet by the undercut portion of the tooth and then by the end of the tooth at a smaller radius on the pallet, the face of the pallet being of a continuous form such that hooking is avoided between the escapement teeth and the pallet.

MARCUS H. RHODES.
